PUSH-BUTTON CONTROL OF SIGNAL
SEEKING RECEIVERSMadison G. Nicholson, Jr., Snyder, N. Y., assignor
to Colonial Radio Corporation, Buffalo, N. Y.

Application October 5, 1944, Serial No. 557,312

13 Claims. (Cl. 250—40)

This invention relates to signal seeking receivers, and more particularly to push button control thereof.

In signal seeking receivers of the usual construction there is provided a motor-operated tuner which may be set in motion by means of a push button when the operator desires to receive a station. The tuner will then scan the spectrum of the receiver until an incoming signal of predetermined strength is received, when the action of the receiver in responding to such incoming signal interrupts the operation of the tuning motor. The receiver will remain tuned to the received signal until the operator again pushes the button, which starts the tuning motor in operation again.

In the usual form of such receiver the operator has no control over what station will be selected by the receiver other than a control of the motor stopping means in response to the strength of signals. Some form of variable bias is usually provided which enables this control to be obtained, but it is undesirable for unskilled operators to have access to such control and, therefore, for most purposes such receivers select signals without any control by the operator, and the receiver will stop on the first signal of predetermined strength which is encountered as the tuning is varied. For the purposes of this invention, a receiver of this type is termed "random signal seeking."

Under certain conditions it is desirable to enable the operator to select a particular station to which he wishes to listen, while still employing the signal seeking principle. This is desirable, for instance, in metropolitan areas where a great many stations may be received with sufficient strength to stop the tuning, and where the listener prefers to listen only to certain particular stations. It is also desirable when a listener has a particular program in mind which is on a particular station at a particular time, and when the listener does not wish to lose time in going through the entire spectrum in a search for the desired station.

In accordance with my invention I have provided means whereby particular stations may be selected by individual push buttons, but in which the receiver still operates on the signal seeking principle and does not require mechanical adjustments, such as the setting of cams and sectors in mechanically operated push button receivers, and in which the receiver, like the usual form of signal seeking receiver, will tune itself exactly to the incoming signal. I term a

receiver according to this invention "preselective signal seeking," to distinguish from "random signal seeking."

Among the objects of my invention may be mentioned the following:

To provide a signal seeking receiver which may be operated like the conventional push button operated receiver to select only particular ones of the stations within range.

10 To provide a receiver of the class described which may, at the user's option, be operated like a conventional push button receiver to select a particular one of a number of predetermined stations, or which may operate as the usual type 15 of random signal seeking receiver, scanning the entire spectrum and tuning in whatever may be on the air at the moment.

It is still a further object of this invention to provide such a receiver in which no adjustments 20 are required by the operator in operating either as a push button receiver or as a conventional signal seeking receiver.

It is still a further object of my invention to provide such a receiver in which the push buttons and signal-seeking button may be located at a point remote from the receiver itself.

Still other objects and advantages of my invention will be apparent from the specification.

The features of novelty which I believe to be 30 characteristic of my invention are set forth with particularity in the appended claims. My invention itself, however, both as to its fundamental principles and as to its particular embodiments, will best be understood by reference to the specification and accompanying drawing, in which the single figure is a circuit diagram of a receiver in accordance with my invention.

As previously stated, the usual signal seeking receiver is provided with a single button control.

40 When the operator pushes this button, the tuner motor is set in operation and the receiver will scan the spectrum included within its range until it tunes in a signal of predetermined strength. Thereupon the tuning is stopped and the receiver 45 remains in tune with the signal which stopped it until the operator again pushes the button starting the tuning, whereupon it will move on until it encounters the next signal of predetermined strength and will stop there.

50 Receivers of this type, when operated in favorable receiving locations, may tune in and stop on as many as thirty or more stations in the spectrum, and if the operator wishes to receive a particular station, he may not wish to spend time 55 going through the spectrum to locate it. I, there-

fore, have provided a series of push buttons, in appearance much like those heretofore employed in push button controlled receivers, each of which will enable the operator to select a particular desired station merely by pushing the button labelled for that station.

It may be helpful in an understanding of the operation of my invention to describe the fundamental principles and the functioning of the various parts in general terms before undertaking the detailed description of the circuit and its operation.

Essentially I achieve the desired result by breaking up the tuning into two sequential steps, the first of which consists in tuning, not to incoming signals, but to a locally-generated oscillation having a frequency differing from the desired station frequency by a small amount, preferably less than 10,000 cycles, and lying in front of the desired station frequency, considering the direction of tuning of the receiver.

Thus, if the receiver tunes from the low frequency end to the high frequency end of the spectrum, the local oscillator frequency will be set less than 10,000 cycles below that of the desired station frequency.

On first pushing the button for the desired station, this local oscillator is set into operation at the preset frequency. Simultaneously, the sensitivity of the receiver is decreased to a point such that it is unresponsive to incoming signals, but will respond only to the local oscillator frequency.

The receiver will then begin to scan the spectrum but will not stop on incoming signals. It will continue to operate until the receiver is tuned to the local oscillator frequency. At this point tuning is interrupted by the response of the receiver to the oscillator frequency. The receiver is now tuned to a frequency less than one channel from the desired station.

As soon as this action is completed and the receiver tuning is momentarily stopped, the special oscillator is put out of action, the sensitivity of the receiver is restored, the motor circuit is again closed by special means which will be described in detail hereafter, and the receiver again begins to vary its tuning at full sensitivity.

At this point it is very near the tuning of the desired signal, and very little change in tuning is required to tune the desired signal exactly. When this occurs, the response of the receiver to the desired signal shuts off the tuner motor and the receiver will remain tuned to the incoming signal until another button is pushed for another desired station, or the signal seeking button is pushed, which sets the receiver into operation, as in the conventional signal seeking receiver.

In this latter condition, as will be understood, this local oscillator is not used, and the receiver operates at normal sensitivity, and will stop at the first signal of predetermined strength.

One way in which my invention may be constructed and operated will now be described with reference to the drawing, which shows my invention as applied to a signal seeking receiver of the superheterodyne type. In the figure, 1 represents the antenna which supplies the converter 2. This converter may be tuned by any suitable tuning instrumentality, herein diagrammatically shown as condenser 3, although it will be understood that other forms of tuning may equally well be employed, such as inductance or permeability tuning.

The converter receives locally generated oscil-

lations of heterodyning frequency from heterodyne oscillator 4 tuned by variable tuning instrumentality 5 ganged with the converter tuning 3 and driven by suitable tuner motor 26. The oscillator may be a separate oscillator or it may be a part of the converter as when a pentagrid converter is used.

The heterodyned oscillations are detected and supplied to the intermediate frequency amplifier 6 and the output of the same may be detected again and amplified at audio frequency by the detector and audio amplifier 7, and supplied to a suitable indicator, such as loud speaker 8. So far the apparatus described is the conventional form of superheterodyne receiver familiar to those skilled in the art and which, therefore, needs no further description.

For the purpose of providing a control voltage to stop and start tuner motor 26, a portion of the output from intermediate frequency amplifier 6 may be fed to limiter 9. Since a limiter is well known in the art, it is not believed necessary to describe it in detail. The output of the limiter may then be supplied to narrow band selector 10. This may take any one of a number of suitable forms, and, for example, may be a crystal selector such as shown and described in the co-pending application of Verlis H. Wiley, Serial No. 554,470, filed September 16, 1944, owned by the assignee of this application.

The band width of selector 10 is preferably made a small fraction of that of intermediate frequency amplifier 6. If the latter has a pass width of 5,000 cycles, for example, then narrow band selector 10 may be given a band pass width of only 500 cycles. This permits the receiver to operate on signals of feeble strength even in the presence of considerable noise and static without false stoppages of the tuning resulting from noise or static. This feature is claimed in the aforementioned application of Verlis H. Wiley and forms per se no part of this invention.

The control tube 28 may be fed by the output from narrow band selector 10, and this tube may be a thyratron having cathode 28c, control electrode 28g, and anode 28a, the control electrode being connected to the output of narrow band selector 10, and also to ground through suitable resistance 27. The anode may be connected to energizing winding 29w of relay 29, and this coil may be shunted by condenser 30, and winding 29w may be connected to +B to provide plate voltage.

Relay armature 29a may be connected to ground and is spring biased to back contact 29b and energized to front contact 29f. Back contact 29b may be connected to the ungrounded lead to the loud speaker, and serves to mute the loud speaker when the armature is in back contact position. In front contact position the armature closes the circuit through energizing winding 30w of relay 30, which includes source of voltage 31.

Relay 30 may operate two armatures 30a₁ and 30a₂, and these armatures may be spring biased to back contact position and energized to front contact position. Front contact 30f₁ may be unconnected. Back contact 30b₁ may be connected to one side of motor 26 and armature 30a₁ may be connected to the other side of the motor through suitable source of current 39. Armature 30a₂ may be connected to +B, and front contact 30f₂ may be connected through condenser 34 shunted by resistance 35 to cathode 28c of tube 28.

Back contact $30b_2$ may be connected through oscillator coil $14s$ to the anode of oscillator 15 . The latter may be a suitable triode having cathode $15c$, control electrode $15g$, and anode $15a$. The cathode may be connected through resistance 37 to ground shunted by condenser 16 , and also to contacts $22a$, $22b$, and $22c$ of switches 22 . Control electrode $15g$ may be connected through resistance 25 to the A. V. C. line leading to the I. F. amplifier 6 , and shunt resistance 24 to ground may also be provided.

Control electrode $15g$ may also be connected through condenser 23 to the common point of condensers $11b$, $12b$, and $13b$, from the other side of which condensers connections may be established through switches $11a$, $12a$, or $13a$ to ground. Said switches may be operated by their associated push buttons 11 , 12 , and 13 , which constitute the individual station buttons, and their operation will be described more in detail later. It may be noted at this point, however, that, while for purposes of simplicity I have shown only three of these, as many more may be provided as desired, although ordinarily five or six would be regarded as sufficient.

The common terminal of condensers $11b$, $12b$, and $13b$ and condenser 23 may be connected through coil $14p$ to ground, and coils $14a$ and $14s$ are preferably coupled to form a feed-back circuit for oscillator 15 . The oscillator frequency will be determined by the setting of condensers $11b$, $12b$, and $13b$, the same being variable, but not provided with operating controls for the user. They are preferably set in a manner which will be hereinafter described and thereafter left alone until it becomes necessary to reset the receiver for different stations.

It will be noted that when armature $30a_2$ is closed against back contact $30b_2$, B voltage is applied through resistances 38 and 37 to ground and also through resistance 38 to conductor 41 . A portion of the oscillator voltage may be picked up by inductance $14a$ coupled to coil $14p$ and $14s$ and thence applied to antenna 1 through suitable condenser 40 .

Push buttons 11 , 12 , and 13 are arranged in the well-known interlocking manner so that only one may be depressed at a time, and the depression of any one releases any other which happens to be depressed. In addition to buttons 11 , 12 , and 13 , which are set for particular stations, there may be provided another push button 17 operating to close switch 20 , having its movable contact connected to ground through conductor 42 , to which are also connected the movable contacts of switches 21 , $22a$, $22b$, and $22c$. The fixed contacts of switches $22a$, $22b$, and $22c$ may be connected to conductor 41 and the fixed contact of switch 21 through resistance 18 to cathode $28c$ of control tube 28 .

Condenser 19 may be connected from one terminal of resistance 18 and through switches 20 and 21 to the other terminal of resistance 18 . The tuning motor ordinarily is arranged for operation in only one direction, and the tuning instrumentality for 360° rotation, and ordinarily a switch (not shown) will be provided for shorting out the signal seeking operation on the return half of the 360° rotation of the tuning instrumentality. This may be done very simply; for example, by providing a switch which short circuits the input to the receiver or opens the space current path of tube 28 during the return half of the rotation of the tuning instrumentality.

Condensers $11b$, $12b$, and $13b$ are preferably

so adjusted that when the particular button associated therewith is closed, the oscillator generates a wave of a frequency differing by a small amount, say a few thousand cycles, from the particular station desired to be received by the operation of that button, and in such direction that the oscillator frequency lies ahead of the desired station, that is, so that oscillator frequency is tuned in before the desired station would be tuned in.

Buttons 11 , 12 , and 13 are arranged with suitable interlocking means such as slider $21a$ so that upon depression of any button, switch 21 is momentarily opened in passing. This interrupts the plate circuit of tube 28 , causing deionization thereof if it happens to be ionized, interrupting the current through relay winding $29w$, and permitting armature $29a$ to fall back against back contact $29b$, thereby muting the loud speaker.

This also interrupts the current in relay energizing winding $30w$, permitting armatures $30a_1$ and $30a_2$ to fall back against their back contacts $30b_1$ and $30b_2$. Closure of $30a_1$ against $30b_1$ closes the motor circuit and starts the motor in operation, varying the tuning. Closure of $30a_2$ against $30b_2$ supplies $+B$ voltage to the plate circuit of oscillator 15 . Closure of any button of the series 11 , 12 , and 13 also momentarily closes one of the switches $22a$, $22b$, or $22c$. This momentarily applies ground to the cathode of oscillator 15 , removing the cut-off bias otherwise applied by the I. R. drop through resistance 37 , and the oscillator 15 will be set into operation at the frequency determined by button 11 , 12 , or 13 . Opening of switches $22a$, $22b$, or $22c$ immediately thereafter restores the bias on tube 15 , but it continues to oscillate, although it will not start with the bias applied.

At the same time, a negative voltage is developed on control electrode $15g$ and applied to the A. V. C. line to substantially reduce the sensitivity of the receiver to a value such that it is no longer responsive to incoming signals, but only to the special oscillator 15 . The receiver will continue to vary its tuning until it tunes in the oscillator frequency, at which time a voltage is applied from narrow band selector 16 to control electrode $28g$ of tube 28 .

This is sufficient to ionize the tube, which begins to pass plate current, closing armature $29a$ against front contact $29f$, and thereby energizing relay winding $30w$ and closing armatures $30a_1$ and $30a_2$ against front contacts $30f_1$ and $30f_2$, interrupting the motor circuit and the plate circuit of tube 15 , stopping the motor and the tuning. However, it will be remembered that the receiver is not yet tuned to the desired signal, but to the frequency of oscillator 15 , differing from the desired signal frequency by a small amount.

Application of $+B$ voltage to contact $30f_2$ applies a surge of positive voltage to cathode $28c$ of tube 28 , which extinguishes this tube and, therefore, armatures $29a$, $30a_1$, and $30a_2$ are released against back contact position. This energizes the motor circuit again, and the motor begins to operate, tuning from the oscillator frequency toward the desired signal frequency.

Now, however, the oscillator 15 does not begin to oscillate as it did before, because of the fact that switches $22a$, $22b$, and $22c$ are open, and a cut-off bias is applied to the oscillator, derived from the connection of cathode $15c$ to the common point of resistances 37 and 38 , so the

tuner will continue to turn until the desired station is tuned in if it is on the air, and when the desired station is tuned in, the narrow band selector applies a voltage to control electrode 28g, which ionizes this tube for the second time, thereby closing armatures 29a, 30a₁, and 30a₂ against their respective front contacts, stopping the motor.

The closure of 30a₂ against its front contact again applies +B voltage to condenser 34, but since this has not had sufficient time to discharge from the previous application of +B voltage, the surge which reaches cathode 28c is not sufficient to extinguish tube 28, and the relays hold in front contact position with the receiver on tune to the desired station.

It is important to note at this point that the tuning of oscillator 15, as determined by buttons 11, 12, and 13, must be made sufficiently close to the desired station frequency so that the receiver will not pick up another station in between the oscillator frequency and the desired station frequency, as this would cause the receiver to stop on the intervening station. It will also be noted that, while this operation is rather lengthy to describe, it occurs very quickly, the stoppage on the oscillator frequency being only momentary, and being evidenced only by a slight clicking of the relays.

It will be noted that the tuning of oscillator 15 does not in any way interfere with the stopping of the tuning when the desired station is tuned exactly, this preliminary stoppage on the oscillator setting being a means of quickly arriving at a point just ahead of tuning in the desired station. The foregoing description applies for operation of any one of buttons 11, 12, and 13, except that the local oscillator frequency will be different in each case.

The adjustment of the local oscillator frequency for the desired stations is an operation which is best performed by a service man with the aid of a second (not signal seeking, however) receiver. One procedure is to tune in both the desired station and the local oscillator on the second receiver, to adjust the local oscillator by varying condenser 11b, 12b, or 13b, as the case may be, to zero beat for the desired station, and then to detune to a small degree so as to shift the oscillator frequency ahead of the desired station frequency by a small amount, not more than 10 kc., preferably somewhat less, say 6 to 8 kc.

To provide for purely signal seeking operation which will receive any station on the air, the operator presses button 17. Upon pushing signal seeking control button 17, the first action which occurs is the release of any of buttons 11, 12, or 13, which may be closed, thus opening the corresponding switch, 11a, 12a, or 13a, and closing switch 20.

At the same time switch 21 is opened, opening the plate circuit of tube 28, and deionizing it if it happens to be ionized. Deionization of tube 28 allows the relays to fall back to back contact position, closing the motor circuit and starting the tuning.

Oscillator 15 will not be operated because switches 22a, 22b, and 22c are open and cathode 15c is biased to cut-off by its elevated potential derived from connection to the common point of resistances 37 and 38. Therefore, the tuning will continue until an incoming signal is tuned in having sufficient strength to ionize tube 28, at which point the relays will be attracted to front

contact position, the motor circuit will be opened, and tuning will be stopped.

Movement of armature 30a₂ to front contact 30f₂ again applies B voltage to condenser 34 and through it to cathode 28c, but since switch 20 is now closed (it being remembered that this switch is closed at all times except when button 11, 12, or 13 is in), condenser 19 absorbs the positive surge and the cathode does not rise sufficiently to extinguish tube 28.

Therefore, the immediate reclosure of the motor circuit which occurs with buttons 11, 12, and 13 does not occur with button 17, and the receiver will remain tuned to the incoming signal until button 17 is again closed, when the operation just described occurs again and the receiver moves on to the next station in the spectrum.

The switch assembly containing buttons 11, 12, 13, and 17 may be made up of a casing containing 20 slotted button plungers 11c, 12c, 13c, and 17c, and plungers 11b, 12b, and 13b may engage locking slider 21a and plain slider 20a, which pass through slots therein, both sliders being moved to the right when a controlling button is pressed.

25 Note that button 17 does not engage or operate slider 20a. When button 11, 12, or 13 is fully depressed, both sliders 20a and 21a are first moved to the right, opening switches 20 and 21, and slider 21a then returns to initial position as, engaging 30 one of fingers 21b with slot 21c of the respective plunger, latching the same in depressed position, closing switch 21, and holding slider 20a at the right-hand position, and keeping switch 20 open. Note also that plunger 17a has no latching slot 35 21c and, therefore, does not latch in.

It is clear that all of the apparatus herein described may be incorporated in the chassis of the receiver if desired, but it will also be understood that the apparatus lends itself readily to a remote control receiver. In this instance the switch assembly may be a separate unit to be mounted at any convenient or desired location, and connected to the chassis by cable, so that in an automobile the chassis might be located under the front seat or in the trunk, and the switch assembly on the steering column or dash.

Also, the push button and special oscillator and associated parts may be made as a special unit available separately to be connected to a conventional signal seeking receiver so as to convert it for push button operation.

While I have shown and described my invention as applied to a superheterodyne receiver, it will be understood that it may equally well be applied to receivers of the T. R. F. type.

While I have shown and described certain preferred embodiments of my invention, it will be understood that modifications and changes may be made without departing from the spirit and scope thereof, as will be clear to those skilled in the art.

In this application I have explained the principles of my invention and the best mode in which I have contemplated applying those principles, so as to distinguish my invention from other inventions; and I have particularly pointed out and distinctly claimed the part, improvement, or combination which I claim as my invention or discovery.

70 I claim:

1. The combination with a signal seeking receiver, having a variable tuning instrumentality, electrical power means for varying said tuning instrumentality, and means operated by said receiver for stopping the variation of tuning in re-

sponse to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent to desired station frequency, means for interrupting both the tuning variation and operation of said oscillator when said receiver is tuned to said oscillator, and means operated by said receiver for restarting said tuning variation immediately thereafter.

2. The combination with a signal seeking receiver, having a variable tuning instrumentality, electrical power means for varying said tuning instrumentality, and means operated by said receiver for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent to desired station frequency and ahead of the desired station frequency in relation to the direction of frequency change in tuning, means for interrupting both the tuning variation and operation of said oscillator when the said receiver is tuned to said oscillator, and means operated by said receiver for restarting said tuning variation immediately thereafter.

3. The combination with a signal seeking receiver, having a variable tuning instrumentality, electrical power means for varying said tuning instrumentality, means operated by said receiver for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent to desired station frequency, means for increasing the required signal strength level necessary to stop said tuning variation while said oscillator is in operation, means for interrupting both the tuning variation and operation of said oscillator when said receiver is tuned to said oscillator, and means operated by said receiver for restarting the tuning variation immediately thereafter.

4. The combination with a signal seeking receiver, having a variable tuning instrumentality, electrical power means for varying said tuning instrumentality, and means for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and oscillation of said oscillator when said signal is tuned to said oscillator, and means operated by said receiver for restarting the tuning variation immediately thereafter.

5. The combination with a signal seeking re-

ceiver, having a variable tuning instrumentality, electrical power means for varying said tuning instrumentality, means for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent to desired station frequency, said means including a bias normally sufficient to prevent said oscillator from starting, but insufficient to stop it after starting, and means for removing said bias on operation of any push button; means for increasing the required signal strength level necessary to stop said tuning variation to a value in excess of that of any incoming signal while said oscillator is in operation, means for interrupting both the tuning variation and oscillation of said oscillator when said signal is tuned to said oscillator, and means operated by said receiver for restarting the tuning variation immediately thereafter.

6. The combination with a signal seeking receiver, having a variable tuning instrumentality, electrical power means for varying said tuning instrumentality, means for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and oscillation of said oscillator when said signal is tuned to said oscillator, means operated by said receiver for restarting the tuning variation immediately thereafter, and means for preventing restarting operation of said oscillator.

7. The combination with a signal seeking receiver, having a variable tuning instrumentality, electrical power means for varying said tuning instrumentality, means for stopping the variation of tuning in response to reception of an incoming signal of predetermined strength; of a push button signal selector including a plurality of push buttons presettable for the selection of individual desired stations respectively, an oscillator, means operated by said push buttons for setting the oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and oscillation of said oscillator when said signal is tuned to said oscillator, means operated by said receiver for restarting the tuning variation immediately thereafter, and means for preventing the restarting of tuning variation when the receiver stops tuning upon the preselected station.

8. The combination with a signal seeking receiver, having a variable tuning instrumentality, electrical power means for varying said tuning instrumentality, and means for stopping the variation of tuning in response to reception of an incoming signal of predetermined strength, said

means comprising a thyratron having a cathode, an anode, and a control electrode, and stopping the electrical power means in response to a signal of predetermined strength; of a push button signal selector including a plurality of push buttons presetable for the selection of individual desired stations respectively, an oscillator, means operated by said push buttons for setting the oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and oscillation of said oscillator when said signal is tuned to said oscillator, and means operated by said receiver for restarting the tuning variation immediately thereafter, said means including means for applying a surge of positive potential to the cathode of said thyratron.

9. The combination with a signal seeking receiver, having a variable tuning instrumentality, electrical power means for varying said tuning instrumentality, and means for stopping the variation of tuning in response to reception of an incoming signal of predetermined strength, said means comprising a thyratron having a cathode, an anode, and a control electrode, and stopping the electrical power means in response to a signal of predetermined strength; of a push button signal selector including a plurality of push buttons presetable for the selection of individual desired stations respectively, an oscillator, means operated by said push buttons for setting the oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and oscillation of said oscillator when said signal is tuned to said oscillator, means operated by said receiver for restarting the tuning variation immediately thereafter, said means including means for applying a surge of positive potential to the cathode of said thyratron, and means for preventing said surge from deionizing said thyratron when the preselected station is tuned.

10. The combination with a signal seeking receiver, having a variable tuning instrumentality, electrical power means for varying said tuning instrumentality, and means for stopping the variation of tuning in response to reception of an incoming signal of predetermined strength; of a push button signal selector including a plurality of push buttons presetable for the selection of individual desired stations respectively, an oscillator, means operated by said push buttons for setting said oscillator into oscillation at a frequency immediately adjacent the desired station frequency, means for increasing the required signal strength level necessary to stop said tuning variation to a value in excess of any incoming signal while said oscillator is in operation, means for interrupting both the tuning variation and

oscillation of said oscillator when said signal is tuned to said oscillator, means operated by said receiver for restarting the tuning variation immediately thereafter, and additional means for starting tuning variation and preventing starting of said oscillator.

11. The combination with a signal seeking receiver, having a variable tuning instrumentality, electrical power means for varying said tuning instrumentality, and means for stopping the variation of tuning in response to reception of an incoming signal of predetermined strength; of a push button signal selector comprising a plurality of push buttons presetable for the selection of individual desired stations respectively, an oscillator, means associated with each of said push buttons for setting the frequency of said oscillator immediately adjacent to the frequency of the desired station, means for initiating operation of said oscillator upon closure of any station selector button, means for reducing the sensitivity of said receiver while said oscillator is in operation, means for applying oscillations from said oscillator to the input of said receiver whereby variation of tuning will be interrupted when the receiver is tuned to the oscillator frequency, means for restarting said variation of tuning immediately upon termination thereof, means for restoring the receiver sensitivity, and means for preventing operation of said oscillator after said restarting.

12. The method of tuning a radio receiver which comprises generating at said receiver currents of a frequency adjacent to the frequency of any one of a plurality of desired station frequencies, conditioning the receiver to be affected only by the currents generated at said receiver, impressing the said currents corresponding to said selected frequencies on said receiver, adjusting the receiver tuning elements, utilizing the current in said receiver to terminate the adjustment of said tuning element when the currents generated at said receiver have been tuned in, thereafter conditioning the receiving apparatus so as to be affected only by incoming signals, again varying the tuning of the receiving apparatus, and utilizing the output of the receiving apparatus at the desired frequency to terminate variation of its tuning.

13. The method of tuning radio receiving apparatus to any selected one of a plurality of different frequencies, which comprises generating at the receiver currents of a frequency adjacent to the preselected frequency but differing therefrom by not more than 10 kc., simultaneously conditioning the receiving apparatus to be affected only by currents generated at the receiver, impressing such generated currents on the receiving apparatus, varying the tuning of the receiving apparatus, utilizing the output of the receiver when tuned to said generated currents to stop the variation of tuning, immediately thereafter conditioning the receiving apparatus to respond only to received signals, again varying the tuning, and utilizing the output of the receiving apparatus to terminate variation of its tuning.
